UNITED STATES PATENT OFFICE

WALTER HAROLD SMITH, OF TORONTO, ONTARIO, CANADA, ASSIGNOR TO BUSINESS SYSTEMS LIMITED, OF TORONTO, ONTARIO, CANADA, A CORPORATION OF CANADA

PRINTING PRESS

Application filed May 28, 1930. Serial No. 456,760.

My invention relates to improvements in printing presses, and the object of the invention is to provide means in a press in which a series of forms or designs with the usual small transverse margin or interspace between the form ends are formed as they are printed on the web to stop the web at one of such marginal interspaces and throw off the impression simultaneously, and means for starting the web and throw on the impression simultaneously within such marginal space so that no printing is missed between the throwing off and the throwing on of the impression, and a further object is to provide a timing means so that regardless of how many forms are carried by the form cylinder that the numbering and perforating units will be effective on each form and the folding on every two forms; and it consists essentially of the arrangement and construction of parts all as hereinafter more particularly explained.

Fig. 1 is a side elevation of a printing press constructed in accordance with my invention and showing the numbering, punching, perforating and folding mechanism diagrammatically.

Fig. 2 is an enlarged elevation of the operating mechanism and showing its connection to the cylinders of the press and relative position of the parts, the supporting standards of the press carrying the mechanism being removed.

Fig. 3 is an end elevation of the press.

Fig. 4 is an enlarged face elevation of the clutch and the tripping levers coacting therewith.

Fig. 5 is a similar view to Fig. 4 showing the means for holding the clutch plate stationary when released.

Fig. 6 is a sectional view through the clutch showing the means for holding the clutch stationary until the impression cylinders are raised into contact.

Fig. 7 is a sectional view through the clutch taken on line 7—7 Fig. 4.

Fig. 8 is a sectional view through the clutch taken on line 8—8 Fig. 4.

Fig. 9 is a sectional view on line 9—9 Fig. 7.

Fig. 10 is a detail view of the manually operated means for raising or lowering the cylinders for the press.

Fig. 11 is an enlarged perspective detail of the means for manually controlling the tripping mechanism and the numbering mechanism.

Fig. 12 shows perspective details of the tripping pawls shown in the relative position they assume.

Figs. 13 and 14 are enlarged perspective details of the clutch rods.

In the drawings like characters of reference indicate corresponding parts in each figure.

1 indicates the main frame of the machine provided with standard plates 2 and 3 connected by the supporting plate 4, the standard plates and supporting plate 4 being located at each side of the machine. The standard plates 2 and 3 carry housings 5 and 6. 7, 8 and 9 are respectively the plate cylinder, transfer cylinder and impression cylinder carried between the standard plates 2 supported on shafts 7^x, 8^x and 9^x. The shafts 8^x and 9^x are mounted in eccentric bearings 10 and 11 in each of the standard plates 2.

A second printing unit consisting of the cylinders 12, 13 and 14 carried on shafts 12^x, 13^x and 14^x between the standard plates 3, the shafts 13^x and 14^x being also mounted in eccentric bearings 15 and 16.

The eccentric bearings 10 and 11 are provided with arms 10^x and 11^x and the eccentric bearings 15 and 16 with arms 15^x and 16^x. The arms 15^x and 10^x are connected by adjustable links 17 and the arms 16^x and 11^x by adjustable links 18. 19 and 20 are rock shafts mounted at their ends in the plates 5 at each side of the machine.

21 is an arm secured to the rock shaft 20 and connected at its outer end by a tension spring 22 to a suitable anchoring point hereinafter described.

The rock shaft 19 is provided with an arm 23 connected by a tension spring 24 to a stationary anchoring point 25. 26 is the main driving or fly wheel shaft upon which is secured a gear pinion 27. The cylinders 7, 8 and 9 are connected together by intermeshing gears 28, 29 and 30, the gear 30 being de-

tachably connected to a cylinder shaft 9^x by clutch mechanism hereinafter described.

The gear 27 of the fly wheel shaft 26 is in meshing contact with the gear 30 so as to drive the gears 29 and 28. The shaft 8^x is provided at one end with a bevel gear 31. 32 is a longitudinal shaft mounted in bearings 33 and 34. 35 is a bevelled gear secured to the cylinder shaft 13^x. 36 and 37 are bevel gears secured to the shaft 32 and meshing respectively with the bevel gears 31 and 35. By this means the cylinder gears 12°, 13° and 14° intermeshing one with the other are driven from the cylinder shaft 8^x. It will thus be seen that the upper cylinders 7 and 12 are driven continuously from the main drive or fly shaft 26.

I will now describe the means by which the cylinders 8 and 9 and 13 and 14 are raised 20 and lowered in and out of their printing position.

38 is an arm carried by the rock shaft 19 and pivotally connected as indicated at 39 to the connecting links 17 extending between 25 the transfer cylinders. 40 is an arm carried by the rock shaft 20 and pivotally connected as indicated at 40^x to the connecting links 18 extending between the impression cylinders. 41 is a collar secured to the shaft 19 and provided with a notch 41^x. 42 is a collar secured to the rock shaft 20 and provided with a notch 42^x.

43 and 44 are studs carried respectively by the standard 2 and plate 4. 45 is a pawl 35 swung upon the stud 44 and spring held at its free end in engagement with the notch 42^x by the tension spring 46. 47 is a pawl mounted upon the stud 43 and spring held in engagement with the notch 41^x by the tension 40 spring 48.

When the pawls 47 and 45 are forced out of engagement with the notches 41^x and 42^x the rock shafts 19 and 20 are turned, the shaft 20 in a clockwise direction and the 45 shaft 19 in a counter clockwise direction. By this means the links 17 and 18 are carried longitudinally in the direction of arrow thereby through the arms 10^x, 15^x, 11^x and 16^x turning the eccentric bearings 11 and 16 50 and 10 and 15 so as to lower the transfer and impression cylinders 8 and 13, 9 and 14 respectively out of their printing position.

I will now describe the combination clutch and tripping mechanism whereby the press 55 is thrown in and out of gear and the transfer and impression cylinders simultaneously carried to their on and off position by the releasing of pawls 45 and 47.

The shaft 9^x of one of the impression cylinders 60 is extended outward from the standard plate 2 and has keyed thereon spaced apart discs 49, 50 and 51. The disc 50 is provided with a central hub 52 through which the extended end of the shaft 9^x also passes 65 such hub forming a spacing means holding

the discs 49 and 50 apart. The gear 30 is provided with a centre orifice 30^x corresponding in size to the size of the hub 52 so as to be freely mounted thereon and normally idle around the hub when the clutch is disengaged. The disc 51 is connected to the disc 50 by means of the spacing studs 53.

Diametrically opposite circular orifices 54 and 55 are formed in the disc 50 and centres of which are in alignment with the surface formed by the exterior periphery of the hub 52 and interior periphery of the gear 30. The orifice 54 is extended through the hub 52 as indicated at 54^x and adjacent portions of the gear 30 as indicated at 54° thereby forming a half orifice in the hub 52 and an opposing half orifice in the gear 30 which are carried into and out of alignment as the gear 30 revolves freely around the hub 52. The orifice 55 is also extended in a similar manner into the hub 52 and gear 30 but the extensions only extend partially through such hub and gear as indicated at 55^x and 55°. The discs 51 are provided with orifices 56 and 57 in central alignment with the orifices 54 and 55.

58 and 59 are clutch rods. The clutch rod 58 is formed by a cylindrical portion 60 turnably fitting the orifice 54 and a segmental cylindrical portion 61 extending therefrom, 95 the face 62 of which is slightly convexed to correspond in curvature to the exterior periphery of the hub 52.

63 is a cylindrical extension at the opposite end of the portion 61 adapted to turnably fit an orifice 64 formed in the disc 49 in axial alignment with the centre of the orifice 54. The outer end of the rod 58 is reduced at 65 extending through the orifice 57 and turnably fits the same, the ends of such 105 portion 65 projecting from the outer face of the disc 51.

The rod 59 is similarly formed to the rod 58 at its outer end, the inner end of the rod, however, is only provided with a short portion 67 corresponding to the portion 61 of the rod 58, such short portion corresponding in length to the orifice extensions 55^x and 55°. The discs 49, 50 and 51 are all keyed to the shaft 9^x. 68 and 69 are gear segments secured to the outer ends of the rods 58 and 59 in meshing relation one with the other so as to ensure of the rods 58 and 59 turning in unison.

70 is a tripping finger which is secured to the rod 58 between the discs 50 and 51. 71 and 72 are stops for limiting the movement of the tripping finger 70. 73 is a tension spring secured at one end to the tripping finger 70 and at its opposite end to an anchoring point 74 formed between the discs 50 and 51. The outer end of the tripping finger 70 normally travels in a circular path indicated by the broken line 75. The pawl 45 is provided with a rearwardly extending 125

finger 45^x which is in alignment with the interspace between the discs 50 and 51 and at its extreme end enters into such interspace and close to the circular path 75 of the tripping finger 70.

76 is a stud carried by the standard plate 2 upon which is mounted a sleeve 77 provided with a stop finger 78 provided at its end with an open ended slot 79. 80 is a short shaft 10 journaled in the standard plate 2 as indicated at 80^x. 81 is a sleeve secured to the outer end of the shaft 80 from which an upwardly extending tripping finger 82 extends, the extreme upper end extending through the slotted end 79 of the stop finger 78, projecting slightly above the same as clearly indicated in Fig. 4 and closely adjacent to the path 75 of the tripping finger 70. The tripping finger 82 is spring held by a spring 83. 84 is a latch 20 which is secured to the shaft 80 to turn therewith.

85 is a shaft extending transversely of the machine and mounted in the standard plates 2. 86 is a sleeve secured to the shaft 25 85 and provided with a rearwardly extending arm 87 and a forwardly extending arm 88. 89 is a heavy tension spring secured at its upper end to the end of the arm 87 and at its lower end to a suitable anchoring point 30 at the base of the press. The sleeve 86 is provided with a segmental extension 90 35 provided in its periphery with a latch engaging notch 91 with which the latch 84 engages when the parts are in their normal or running position.

When it is desired to stop the machine the stop-pawl 78 is swung from the full line position indicated in Fig. 4 to the dotted line position indicated in the same figure so as to extend across the circular path 75 of the tripping pawl 70.

As the clutch revolves the tripping finger 70 engages the end of the stop finger 78 and is thereby forced into the dotted position indicated in Fig. 4 and simultaneously against the end of the tripping finger 45^x forcing such tripping finger 45^x downward and thereby raising the engaging end of the pawl 45 out of the notch 42^x of the collar 42 thereby releasing the collar and the shaft 20 so that it is revolved in a clockwise direction by the spring 46 which movement carries the link 18 in the direction of arrow to throw the impression cylinders to their off position.

55 By the tripping of the shaft 20 as above described mechanism is operated whereby the collar 41 and shaft 19 are released which mechanism I will now describe.

92 is an arm carried by the shaft 20. 93 is 60 a tripping member pivotally mounted at 94 upon the arm 92 and provided intermediate of its height with a lateral projection 95. The tripping member is spring held to any suitable anchoring point by a spring 93^x. The upper end of the tripping member 93 is in-

clined as indicated at 93^x. 96 is a rectangular pin carried by a suitable portion of the plate 4 and with which the upper inclined end 93^x is carried into engagement by the clockwise movement of the released rocking shaft 20.

When the rocking shaft 20 is released by the finger 45 to throw off the impression cylinders by the same operation, the lateral projection 95 is carried into engagement with the tail end of the latch 47 carrying it out of engagement with the notch 41^x so as to release the shaft 19 which is then moved counter clockwise so as to carry the links 17 also in the direction of arrow and carry the transfer cylinders to the off position.

When the tripping member 93 is carried to its extreme upward position it engages the pin 96 thereby carrying the projection 95 clear of the latching lever 47 so as to free it and permit its engaging end to resiliently bear against the collar 41.

As the tripping finger 70 operates as above described it turns the clutch rod 58 so that the face of the portion 61 is carried into a position flush with the periphery of the hub 90 52. The corresponding surface of the clutch rod 59 is carried into the same position through the medium of the intermeshing gear segments 68 and 69 so that the driving connection between the gear 30 and impression 95 cylinder shaft 9^x is broken.

97 is a bar provided at one end with a longitudinal slot 98 and at its opposite end with a rod portion 99 which is threaded as indicated at 100. 101 is a block pivotally mounted upon the segmental portion 90 and through which the threaded portion of the rod 99 extends. It will be seen that the pin 40^x forming the pivotal connection between the arm 40 and link 18 will be carried to the opposite 105 end of the slot 98 by the release of the rocking shaft 20.

When it is desired to re-engage the clutch and simultaneously carry the impression cylinders to their operative positions the stop finger 78 is swung downward from the dotted line position shown in Fig. 4 to the full line position.

By this means the upper end of the finger 82 extends in an upwardly projecting position above the stop finger 78 and as the clutch mechanism revolves the finger 70 which is in the dotted position engages the upwardly projecting end of the finger 82 moving it against the tension of the spring 83 and thereby carrying the dog 84 out of the notch 91 thereby freeing the segment 90 and the sleeve 86 so that such sleeve is revolved by the pull of the spring 89 revolving the shaft 85 in the same direction and pulling the car 125 longitudinally in the direction of arrow see Fig. 2 carrying the pin 40^x from its dotted line position back to its normal position and thereby pulling the link rods 18 in a corresponding direction so as to reset the impres- 123

sion cylinders in the printing position, and at the same time, drawing down the tripping member 93 into position to refunction when it is again necessary to throw the transfer cylinder out of operation.

It will be noted that the lower end of the spring 22 is anchored to a long arm 103 also carried by the sleeve 86. By this means, it will be seen, that when the spring 89 functions after the releasing of the dog 84 the arm 103 will swing upward relieving the tension of the spring 22 thereby permitting of the shaft 20 being rocked back to its normal position without being opposed by the full tension of the spring 22.

In order to reset the dog 84 and quadrant 90 I provide a cam 104 secured to the main driving or fly wheel shaft 26, an arm 105 being pivotally mounted upon a cross shaft 106 at one end and pivotally connected to the upper end of the link 107 which is pivotally connected at its lower end to the arm 88 of the sleeve 86.

108 is a roller which is revolvably mounted upon the pin forming the pivotal connection between the arm 105 and link 107, such roller contacting with the periphery of the cam 104.

It will be understood that the device is so timed that when the dog 84 releases the segment 90 that the short radius of the cam 104 is opposite the roller 108 thereby providing for the free upward movement of the link 107. It will also be understood that the shaft 26 is a continuously revolving shaft, and that therefore, as soon as the tripping of the dog has been effected the major radius of the eccentric will come into operation to reset the dog.

I will now describe the means by which 40 the stop finger 78 is set for producing the lowering or raising operation of the transfer and impression cylinders.

When the stop finger 78 is in its downwardly swung position the tail piece 78^x of 45 such lever bears against a stop 109 carried by a suitable portion of the machine. 110 is a short shaft mounted in bearings 111 and 112. 113 is a sleeve secured to the shaft 110 and provided with an arm 114 connected by 50 a link 115 to the tail piece 78^x. When the arm 114 is swung downward the link 115 is carried forward carrying the tail piece 78^x in a corresponding direction and swinging the stop finger 78 upward into the path of the 55 tripping finger 70 as hereinafter described.

116 is a divided sleeve, the members of which are spaced apart to form a groove 117 across which extends diametrically opposite pins 118 and 119. 120 is a bracket carried 60 by the standard plate 2.

121 is a bracket carried by the standard plate 3, the brackets 120 and 121 being provided with bearing portions 120^x and 121^x in which is journalled a longitudinally extending shaft 123. 124 is a sleeve secured to the 65

shaft 123 and provided with an arm 125. 126 is a block which is mounted to swivel on the end of the arm 125. 127 is a rocking detent pivotally mounted upon the block 126 to swing at right angles to the arm 125. The 70 detent 127 is provided with opposing fingers 128 and 129 provided at their inner side with notches 130 and 131.

132 and 133 are bearing pieces carried by the bracket 120 and in which is journalled a 75 shaft 134 provided with a handle 135 by which the shaft may be rocked manually. 136 is a crank arm secured to the opposite end of the shaft 134 and carrying a pin 137. 138 is a pin carried by the detent 127 and 139 is 80 a tension spring secured at one end to the pin 137 and the opposite end to the pin 138.

When the handle 135 is in the position shown in the drawings with the crank arm 136 extending to the right hand side of the shaft 134 the pull of the spring 139 carries the detent 127 in a corresponding direction that is towards the right so that the notch 131 is brought beneath the pin 118. When the handle 135 is moved over to the right 90 hand side of the shaft 134 the crank arm 136 is carried to the left of the shaft 134, and therefore, the pull of the spring 139 draws the detent 127 in the opposite direction so that the notch 130 will be carried beneath the pin 119. 95

140 is a sleeve also secured to the shaft 123. The sleeve 140 is provided with an arm 141. 142 is a gear pinion secured to the end of the shaft 32. 143 is a gear mounted upon a suitable supporting stud carried on the frame of the machine and with which the pinion 142 meshes. 144 is a cam formed integral or revolving in unison with the gear 143. 145 is a rod pivotally connected at its lower end to the arm 141 and provided towards its upper end with a longitudinal slot 146 through which the outer end of the stud upon which the cam 144 is mounted extends. 105

147 is a cam roller mounted upon a pin 148 carried by the upper end of the rod 145. As the cam 144 revolves it imparts longitudinal movement to the bar 145 once in each revolution thereby rocking the shaft 123 and reciprocating the arm 125 up and down imparting a like movement to the detent 127. 110

When the machine is in the running position the pins 118 and 119 assume the position illustrated by full lines in Fig. 10. If it is desired to throw the machine out of operation 120 the handle 135 is swung over to the opposite side of the shaft 134 so that the detent is swung towards the dotted line position and as the arm 125 is reciprocated the notch 130 is carried beneath the pin 119 so that by the 125 next upward movement of the detent the pins 119 and 118 are carried to the dotted line position. By this means the arm 114 is carried in the direction of arrow see Fig. 11 forcing the stop finger 78 upward to operate the 130

clutch to release in the manner above described, and simultaneously disengage and carry the impression and transfer cylinders to the off position.

- 5 During this operation it is essential that the machine be slowed down. In order that this will automatically take place I provide a handle 135 with the cam 149. 150 is a switch provided with a pressure button 151.
- 10 When the handle 135 is thrown over in either direction the cam 150 engages the pressure button 151 so as to operate the slowing down switch to slow down the mechanism to the required speed during the change from one position to another.

In order to insure that the clutch mechanism together with the arm 70 is not carried forward upon the lowering of the stop lever 78 I have provided a brake shoe 152 pivotedly mounted on the stud 44 and provided with a brake shoe 153 engaging the periphery of the disc when in its lowered position as indicated by dotted lines in Fig. 6, the arm 150 supported by an adjustable set screw 154. It will thus be seen that when the stop lever 78 is lowered the clutch mechanism cannot immediately start to revolve owing to its frictional contact with the idler gear 30 and cannot revolve until the impression cylinder is raised so as to carry the clutch out of contact with the brake shoe. If it were allowed to slightly revolve as soon as the stop lever 78 is lowered, in the position the arm 70 would assume, it may be possible that such arm would miss the tripping finger 82. It is for this purpose that the brake shoe 153 is provided.

A dog 156 is also mounted upon the stud 44 and spring pressed against the periphery of the disc 51 by the spring 157 carried by the stop finger 78. When the stop finger 78 is raised and engaged by the tripping finger 70 such tripping finger is carried against the stop 72 thereby definitely checking the rotation of the clutch mechanism in a counter-clockwise direction, the dog 156 simultaneously slipping behind the projection 155 preventing the rotation of the clutch mechanism in a clockwise direction and thereby definitely stopping the impression cylinder at a definite point without any danger of slippage.

In order that the numbering, punching, perforating and folding mechanism is driven in unison with my machine a gear 158 is secured to the opposite end of the impression cylinder shaft 9. 159 is a gear mounted upon the stud 160. 161 is a bevel gear formed integral with the gear 159. 162 is a shaft extending longitudinally of the machine and mounted in suitable bearings 163. The impression cylinder 14 is connected to the shaft 162 by gears corresponding to the gears 158, 159, and 161 the shaft 162 being provided with bevel gears 164 meshing with the gears 161 of the impression cylinders 9 and 14.

Punching, numbering and perforating mechanism is also driven from the shaft 162 as indicated at 165 and 166 to operate three times in each revolution of the impression cylinder.

167 is a vertical shaft connected by bevel gears 168 and 169 to the shaft 162. The upper end of the shaft 167 is provided with a bevel gear 170 meshing with the bevel gear 171 mounted upon a transverse shaft 172 to which is secured a feed roller 173 coacting with the feed roller 174 between which the web 175 is drawn to be folded by suitable folding mechanism in the position indicated at 176. 177 is a shaft upon which is secured a short lever 178 provided with a set screw 179 adjacent its end.

180 is a disc provided with a transverse groove 181 and diametrically opposite set pins 182 and 183 extending from the face thereof. 184 is a sleeve secured to the shaft 123 and provided with an arm 185 which operates in unison with the arm 141. 186 is a block similar to the block 126 swivelled on the arm 185 and to which is pivotally connected a vertically movable bar 187. The upper end of the bar 187 is provided with a reduced portion 188 forming notches 189 and 190 on each side thereof and adapted to be swung alternately to a vertical position beneath the pins 182 and 183.

191 is a supporting bar secured to the main frame of the machine and between which and the disc 180 the vertical movable bar 187 extends thereby supporting such vertical bar in place. 192 is a crank handle pivoted to the supporting bar 191 at its lower end and provided with a pin 193 at its upper end forming a hand grip. 194 is a pin extending from the bar 187 and 195 is a tension spring extending between the pin 193 and the pin 194.

It will thus be seen that when the crank handle 192 is swung to the left hand side of its pivot that the pull of the spring 195 will draw the upper end of the bar 187 in a corresponding direction carrying the notch 190 into operative relation with the pin 183 similarly when the crank handle is swung to the opposite side of its pivot the bar 187 will be drawn in the opposite direction so as to carry a notch 189 into position to coact with the pin 192.

When the bar 187 is in position to engage the pin 183 or in the position shown in the drawings the next vertical movement of the bar 187 will turn the disc 180 so that the screw 179 will drop into the groove 181 and thereby swing the cam arm 196 which is also secured to the shaft 177 out of its operative position with the crank 197 of the numbering mechanism.

When it is desired to operate the numbering mechanism all it is necessary to do is to swing the crank arm 192 to the opposite side of its central swing so that the notch 189 is vertically beneath the pin 182 which is in its

lowered position. When the bar 187 moves upward the notch 189 engages the pin 182 turning the disc 180 so as to force the set screw 179 outward and thereby forcing the cam arm 196 inward towards the operating crank 197 of the number mechanism. The numbering mechanism will then operate continuously three times in every revolution of the impression cylinder so as to impress a number on each fold of the web.

Having described the principal parts involved in my invention I will briefly describe the operation of the same.

The press as shown is in the running position that is with the clutch rods 58 and 59 in the engaged position and the impression and transfer cylinders in raised or printing position.

It must be first stated that in order that the imprint on the web remains in the correct position in relation to the folds thereof during the starting and stopping of the press that the stopping and the breaking of the printing contact occurs simultaneously taking place definitely at the point where the printing surface of the plate cylinder is in the position of ceasing to coact with the transfer and impression cylinders, or in other words, at the end of the plate printing surfaces as indicated at the point α and that the restarting and making of the printing contact take place definitely at the beginning of the plate printing surface or at the point where the printing surface of the plate cylinder is in the position of commencing to coact with the transfer and impression cylinders as indicated at the point α^1 . It will thus be seen that the whole action of stopping, breaking printing contact, restarting and remaking printing contact occurs between the points α and α^1 . The printing surface comprising the remainder of the periphery of the printing cylinder is in three sections corresponding to the three surfaces of each double fold of the web.

When it is desired to stop the press the handle 135 is moved over to the right of the shaft 134. This operation actuates the switch 150 by depressing the button 151 so as to slow down the press as the stopping operation is effected. This movement of the handle 135 rocks the shaft 134 so as to swing the crank arm 136 to the left hand side of the rod 134 carrying the lower end of the spring 139 in the same direction. As soon as the spring 139 arrives in the last mentioned position it exerts a pull on the detent 127 swinging it on its pivot to the left carrying the notch 130 towards the pin 119. As the detent is constantly reciprocated vertically by the cam 147, link bar 145, arm 141, rock shaft 123 and arm 125 during its downward stroke such notch is drawn by the spring 139 beneath the pin 119 so that at the next upward stroke of the detent the notch engages such pin carrying it upward to the dotted

position shown in Fig. 10 and thereby rocking the shaft 110 in a corresponding direction. By the rocking movement of the shaft 110 the arm 114 is also carried down forcing the link 115 forward towards the press thereby swinging the free end of the stop finger 78 upward into the dotted position indicated in Fig. 4 between the discs 50 and 51 and into the path of the tripping finger 70 which is revolving with the clutch. 75

As the finger 70 engages the stop finger 78 it is swung towards the dotted position of Fig. 4 against the tension of the spring 73 and during such movement the end of the finger 70 moves vertically downward against the end face of the finger 78 finally engaging the stop 72. Upon the finger 70 arriving at this position the dog 156 normally bearing against the periphery of the disc 51 travels over the stop 155 and is forced into the dotted position of Fig. 5 by the spring 157 on the upwardly raised stop finger 78. 80

It will thus be seen that the disc 51, impression cylinder shaft 9^x and impression cylinder is locked from the slightest movement 90 in a counter clockwise direction by the finger 70 engaging the stop finger 78 and from the slightest clockwise movement by the dog 156 engaging the stop 155. 85

As the finger 70 is swung to the dotted position it also turns the clutch rod 58 to which it is secured and by means of the intermeshing gear segments 68 and 69 simultaneously turning the clutch rod 59 turning their faces 62 and 62^x flush with the periphery of the hub 52 and thereby freeing the gear 30 from driving engagement. Also as the end of the finger 70 is carried downward it engages the rearwardly extending finger 45^x of the pawl 45 raising such pawl out of engagement with the notch 42^x of the collar 42 secured to the shaft 20 thereby freeing such shaft allowing it to rock in a clockwise direction under the tension of the spring 22 connected to the arm 21 also secured to the shaft 20. 100 105 110

The above rocking movement of the shaft 20 swings the arm 40 towards the left carrying the links 18 in a corresponding direction so as to turn the eccentric bearings 16 and 11 to lower the impression cylinders. Also by the clockwise movement of the shaft 20 the arm 94 is swung upward raising the spring held tripping member upward and the lateral projection 95 thereof into engagement with the tail end of the latch pawl 47 disengaging the latch from the notch 41^x of the collar 41 secured to the shaft 19 thereby freeing such shaft to rock in a counter clockwise direction under the tension of the spring 24 connected to the arm 23 also secured to the shaft. 115 120 125

The above rocking movement of the shaft 19 carries the links 17 also longitudinally to turn the eccentric bearings 15 and 10 to lower the transfer cylinder out of print- 130

ing contact. It will thus be seen that the clutch mechanism is thrown out of gear and the cylinders of the press stopped definitely at a predetermined point controlled by the 5 cam 147 and the impression and transfer cylinders lowered from their printing position simultaneously definitely at that point.

When the impression cylinder 9 is lowered as above described the clutch mechanism including the disc 50 is carried down with it so that the periphery of such disc is carried into engagement with the brake shoe 153 thereby definitely holding the cylinders from rotation until again lifted to the printing 10 position which operation I will now describe.

When it is desired to restart the press the transfer cylinders are first manually raised to the printing position by the handle 41° 20 against the tension of the spring 24. The handle 138 is then returned to the position shown in the drawings the cam 124 again engaging the switch button 151 to slow down the press. Also when the parts are in the 25 position shown the detent 127 is drawn back to the full line position by the spring 139 carrying the notch 131 towards the pin 118 which is in the dotted line position and as the detent is reciprocated vertically as above 30 described it engages the pin 118 to carry from the dotted line position back to the full line position thereby rocking the shaft 110 in a clockwise direction to swing the arm 114 upward so as to pull upon the link 115 and 35 swing the stop finger out of the path of the finger 70 and into such a position that the upper end of the tripping finger 82 projects above the same into the path of the finger 70 when returning from its dotted line position 40 to its normal or running position.

When the stop finger is lowered the tripping finger 70 is held from engaging the finger 82 by the locking portions of the clutch rods engaging the interior periphery of the 45 gear 30 preventing the forward swing of the finger 70 until the half orifices 54° and 55° register with the half orifices 54° and 55° permitting the clutch rods to turn by the 50 tension of the spring 73 carrying the finger 70 into engagement with the stop pin 71 and forming a driving connection between the gear 30 and impression cylinder shaft 9. When this takes place the tripping finger 70 engages the projecting end of the finger 82 55 forcing it towards the right against the tension of the spring 83. By this means the shaft 80 is rocked in a clockwise direction carrying the dog 84 out of the notch 91 freeing the sleeve 86 to turn clockwise under the tension of the spring 89 the eccentric 104 being so turned that the short radius thereof is then opposite the roller 108 permitting the upward movement of the bar 107 and arm 88. The clockwise rocking movement of 60 the sleeve 88 and segmental portion 90 pulls

the bar 97 in the direction of arrow drawing the pin 40° from its dotted position back to its normal or full line position rocking the shaft 20 and collar 42 also back to its normal position raising the impression cylinders to the printing position and enabling the pawl 45 to re-engage.

It will be noted that during the return rocking movement of the shaft 20 the resistance of the spring 22 to the raising of the impression cylinder is eliminated by the upward movement of the arm 103 to which the spring 22 is attached. By the same operation the member 93 is also carried back to its normal position.

The continued revolution of the eccentric 104 forces the bar 107 longitudinally downward rocking the sleeve 86 in a counter clockwise direction so as to draw the spring 89 again into tension so as to be stretched or reloaded for the next operation, the pawl 84 80 re-engaging the notch 91.

By the rocking movement of the shaft 123 the stop finger 78 is moved to the "on" or "off" position by mechanism manually set and the 90 numbering mechanism is also moved to the "on" and "off" position by a mechanism which is also manually set. The numbering mechanism by the rocking movement of the shaft 123 is set to the "on" or "off" position by the 95 notches 189 and 190 of the thrust bar 187 engaging the pins 182 or 183 and turning the disc so that the set screw 179 is carried radially in and out to set the cam arm 196 in the operative or inoperative position according to 100 which side of the bar 187 the pin 183 of the crank handle 192 is swinging.

It may be stated that a pair of clutch members 61 and 67 are provided which when set as shown in Fig. 9 will permit of the drive in one direction being taken by the projecting portion of the clutch member 61 and in the other direction by the projecting portion of the clutch member 67. The clutch member 67 prevents the member 61 from entering the part orifice 54° until the member 61 is in full registering position with the part orifice 55°. Therefore, when the part orifices 54° and 54° are in registering position, the rear edges of these part orifices are in a line. The member 61 is then turned to a projecting position definitely engaging the gear 30 and hub 52 when these edges reach an aligned position. If the member 61 were the only clutch member used such clutch member would begin to turn into the part orifice 54° before the part orifice came to a completely registering position and the part orifice would then travel past the registering position, the rear edge of the part orifice 54° engaging the member 61 midway of 110 the part orifice 54° changing the time of engagement. The part orifices 55 and 55° are made short so that the member 61 cannot engage therewith and permit the drive being started at another point than that desired.

From this description it will be seen that I have devised means whereby a press of this type may be started or stopped and the cylinders placed in and out of their printing position by a movement so quickly and closely coinciding with the definite starting and stopping of the press without any lost motion.

What I claim as my invention is:

1. In a printing press of the type described, the combination with the impression cylinder, impression cylinder shaft and driving mechanism, of a clutch device for engaging or disengaging the impression cylinder shaft and drive, and means automatically actuated by the opening and closing of the clutch for moving the impression cylinder in and out of its printing position.

2. In a printing press of the type described, the combination with the impression cylinder, impression cylinder shaft, printing cylinder and driving mechanism, of a clutch device for engaging and disengaging the impression cylinder shaft and drive, means actuated by the opening and closing of the clutch for moving the impression cylinder in and out of the printing position, and timing means whereby the closing of the clutch and simultaneous moving of the impression cylinder into the printing position is effected at the beginning of the printing surface and the opening of the clutch and simultaneous moving of the impression cylinder from the printing position is effected at the end of the printing surface.

3. In a printing press of the type described, the combination with the impression cylinder, impression cylinder shaft, transfer cylinder and plate cylinder, of a clutch device for engaging and disengaging the impression cylinder with the drive, means actuated by the opening and closing of the clutch for moving the impression cylinder in and out of its printing position, and means actuated by the impression cylinder moving means for moving the transfer cylinder in and out of its printing position.

4. In a printing press of the type described, the combination with the impression cylinder and the driving mechanism, of a clutch for engaging the impression cylinder with the drive at a predetermined point, means for locking the cylinder from rotation upon release from the drive, means for lowering the impression cylinder at the point of drive release, and means for raising the impression cylinder at the point of drive engagement.

5. In a printing press of the type described, the combination with the impression cylinder and driving mechanism, of a clutch for throwing the impression cylinder in and out of driving engagement at definite predetermined points in its rotation, means for lowering the impression cylinder from the printing position at the point of clutch release and for raising the impression cylinder to the printing position at the point of clutch engage-

ment, and means for positively locking the released impression cylinder from rotation until raised.

6. In a printing press of the type described, the combination with the impression cylinder and driving mechanism, of a clutch for throwing the impression cylinder in and out of driving engagement at definite predetermined points in its rotation, means for lowering the impression cylinder from the printing position at the point of clutch release and for raising the impression cylinder to the printing position at the point of clutch engagement, a disc secured to the impression cylinder shaft, and a brake shoe with which the disc is lowered into contact by the lowering of the impression cylinder.

7. In a printing press of the type described, the combination with the impression cylinder and driving mechanism, of a clutch for throwing the impression cylinder in and out of driving engagement at definite predetermined points in its rotation, means for lowering the impression cylinder from the printing position at the point of clutch release and for raising the impression cylinder to the printing position at the point of clutch engagement, and means for locking the impression cylinder from rotation when released.

8. In a printing press of the type described, the combination with the impression cylinder and driving mechanism, of a clutch for throwing the impression cylinder in and out of gear at definite predetermined points in its rotation, a clutch operating finger; means for lowering the impression cylinder from the printing position at the point of clutch release and for raising the impression cylinder at the point of clutch engagement, a stop device with which the clutch operating finger engages as it operates to release to prevent counter clockwise rotation of the cylinder, and a peripheral projection carried by the clutch and a coacting dog simultaneously engaging therewith to prevent clockwise rotation.

9. In a printing press of the type described, the combination with the impression cylinder shaft and driving mechanism, of a cylindrical clutch body secured to the shaft, a gear forming part of the drive idly carried on the clutch body, clutch means for engaging the clutch body and gear, a spring held operating finger pivotally mounted to control said clutch means and to travel at its free end in a circular path around the shaft, a stop member carried by the press and movable in and out of the path of the operating finger, means for automatically moving the stop member, and manually adjusted means for placing the stop moving means in actuating relation to move the stop up or down.

10. In a printing press of the type described, the combination with the impression cylinder shaft and driving mechanism; of a cylindrical clutch body secured to the shaft, a

- gear forming part of the drive idly carried on the clutch body, clutch means for engaging the clutch body and gear, a spring held operating finger pivotally mounted to control said clutch means and to travel at its free end in a circular path around the shaft, a stop member carried by the press and movable in and out of the path of the operating finger, means for automatically moving the stop member, and manually adjusted means for placing the stop moving means in actuating relation to move the stop up or down, and means for timing such actuation.
11. In a printing press of the type described, the combination with the impression cylinder shaft and driving mechanism, of a cylindrical clutch body secured to the shaft, a gear forming part of the clutch drive idly carried on the clutch body, clutch means for engaging the clutch body and gear, a spring held operating finger pivotally mounted to control said clutch means and to travel at its free end in a circular path around the shaft, a stop member carried by the press and movable in and out of the path of the operating finger, means for automatically moving the stop member, comprising a transverse rock shaft, a link and lever connection between the rockable shaft and stop member, pins carried in diametrically opposite position at each side of the rock shaft, a longitudinal rock shaft, an arm carried by the longitudinal rock shaft, a link bar pivotally connected thereto, a cam driven from the drive mechanism and coacting with the link bar to reciprocate the same vertically, an oppositely notched member reciprocated vertically by the rocking of the longitudinal rock shaft, and manual means for adjusting the notched member so that one or other of the notches engage a corresponding pin on the transverse rock shaft.
12. In a printing press of the type described, the combination with the impression cylinder shaft and driving mechanism, of a cylindrical clutch body secured to the shaft, a gear forming part of the clutch drive idly carried on the clutch body, clutch means for engaging the clutch body and gear, a spring held operating finger pivotally mounted to control said clutch means and to travel at its free end in a circular path around the shaft, a stop member carried by the press and movable in and out of the path of the operating finger, means for automatically moving the stop member, comprising a transverse rock shaft, a link and lever connection between the rockable shaft and stop member, pins carried in diametrically opposite position at each side of the rock shaft, a longitudinal rock shaft, means for rocking the longitudinal rock shaft from the driving mechanism, an oppositely notched member reciprocated vertically by the rocking of the longitudinal rock shaft, and manual means for adjusting the notched member so that one or other of the notches engage a corresponding pin of the transverse rock shaft.
13. In a printing press of the type described, the combination with the impression cylinder shaft and driving mechanism, of a cylindrical clutch body secured to the shaft, a gear forming part of the clutch drive idly carried on the clutch body, clutch means for engaging the clutch body and gear, a spring held operating finger pivotally mounted to control said clutch means and to travel at its free end in a circular path around the shaft, a stop member carried by the press and movable in and out of the path of the operating finger, means for automatically moving the stop member, comprising a transverse rock shaft, a link and lever connection between the rockable shaft and stop member, pins carried in diametrically opposite position at each side of the rock shaft, a longitudinal rock shaft, an arm carried by the longitudinal rock shaft, a link bar pivotally connected thereto, a cam driven from the drive mechanism and coacting with the link bar to reciprocate the same vertically, an oppositely notched member reciprocated vertically by the rocking of the longitudinal rock shaft, and manual means for adjusting the notched member so that one or other of the notches engage a corresponding pin on the transverse rock shaft.
14. In a printing press of the type described, the combination with the impression cylinder, impression cylinder shaft and driving mechanism, of a clutch device for engaging or disengaging the impression cylinder shaft and drive, means actuated by the opening and closing of the clutch for moving the impression cylinder in and out of its printing position, and means for automatically slowing down the press during the aforesaid operations.
15. In a printing press of the type described, the combination with the impression cylinder and driving mechanism, of a cylindrical clutch body secured to the shaft, a gear forming part of the clutch drive idly carried on the clutch body, clutch means for engaging the clutch body and gear, a spring held operating finger pivotally mounted to control said clutch means and to travel at its free end around the impression cylinder shaft, a movable stop member carried by the press, means for automatically moving the stop member in and out of the path of the operating lever, a spring actuated rock shaft, means for lowering the impression cylinder by the rocking of such shaft, a latch device holding the rock shaft stationary against spring tension and a tripping finger for the latch engaged by the end of the clutch actuating finger as it passes down the end face of the stop finger during the rotation of the clutch body.
16. In a printing press of the type de-

- scribed, the combination, with the impression cylinder, transfer cylinder and the driving mechanism, of a cylindrical clutch body secured to the shaft, a gear forming a part 5 of the clutch drive idly carried on the clutch body, clutch means for engaging the clutch body and gear, a spring held operating finger pivotally mounted to control said clutch means, a lower spring actuated rock shaft 10 releasably held against spring tension, means actuated by the released rock shaft for carrying the impression cylinder out of the printing position, means coacting with the clutch operating finger for releasing the lower rock shaft 15 70 75 75 80 85 90 95 100 105 110 115 120 125 130
- 16 spring actuated rock shaft, an upper spring actuated rock shaft releasably held against spring tension, means actuated by the released upper rock shaft for carrying the transfer cylinder out of the printing position, 20 and means actuated by the lower rock shaft for releasing the upper rock shaft.
17. In a printing press of the type described, the combination with the impression cylinder, transfer cylinder and the driving mechanism, of a cylindrical clutch body secured to the shaft, a gear forming part of the clutch drive idly carried on the clutch body, clutch means for engaging the clutch body and gear, a spring held operating finger 25 pivotally mounted to control said clutch means, a lower spring actuated rock shaft releasably held against spring tension, means actuated by the released rock shaft for carrying the impression cylinder out of the printing position, means coacting with the clutch operating finger for releasing the spring actuated rock shaft, an upper spring actuated rock shaft, a spring held latch pawl for holding the upper rock shaft against 30 35 40 45 50 55 60 65 70 75 80 85 90 95 100 105 110 115 120 125 130
- 41 spring tension, means actuated by the released upper rock shaft for carrying the transfer cylinder out of the printing position, an arm carried by the lower rock shaft, a spring held tripping member carried by 46 the arm and having a lateral projection engaging the tail of the spring held latch pawl to release the same during the rocking of the lower rock shaft, and means for tripping the tripping member out of engagement with the 50 pawl tail to release the same after the rocking of the upper rock shaft.
18. In a printing press of the type described, the combination with the impression cylinder and driving mechanism, of a clutch 55 for engaging the impression shaft and the driving gear, a spring actuated rock shaft, means operated by the rocking of the shaft for moving the impression cylinder out of the printing position, means for simultaneously 60 releasing the rock shaft and opening the clutch, and means for simultaneously returning the rock shaft to the latched position and closing the clutch.
19. In a printing press of the type described, the combination with the impression

- cylinder and driving mechanism, of a clutch for engaging the impression shaft with the driving gear, a spring actuated rock shaft, means operated by the rocking of the shaft for moving the impression cylinder out of the printing position, means for simultaneously releasing the rock shaft and opening the clutch, means for simultaneously returning the rock shaft to the latched position and for closing the clutch, and means for automatically releasing the rock shaft from spring tension during its return movement. 20. In a printing press of the type described, the combination with the impression cylinder and the driving mechanism, a clutch, a clutch actuating finger and stop finger, of a spring actuated rock shaft releasably held against spring tension, means operated by the rocking of the rock shaft when released for moving the impression cylinders out of their printing position, an arm extending from the rock shaft, a rocking segment mounted in the press, a pull bar connecting the segment to the arm, a tension spring connected to the segment so as to exert a pull on the pull bar, a latch pawl holding the segment against spring tension, and a tripping finger connected to the latch pawl and extending past the lowered stop finger and into the path of the clutch operating finger as it is freed by the stop finger and returns to the press running position. 21. In a printing press of the type described, the combination with the impression cylinder and the driving mechanism, a clutch, a clutch actuating finger and stop finger, of a spring actuated rock shaft releasably held against spring tension, means operated by the rocking of the rock shaft when released for moving the impression cylinders out of their printing position, an arm extending from the rock shaft, a rocking segment mounted in the press, a pull bar connecting the segment to the arm, a tension spring connected to the segment so as to exert a pull on the pull bar, a latch pawl holding the segment against spring tension, a tripping finger connected to the latch pawl and extending past the lowered stop finger and into the path of the clutch operating finger as it is freed by the stop finger and returns to the press running position. 22. In a printing press of the type described, the combination with the impression cylinder and the driving mechanism, a clutch, a clutch actuating finger and stop finger, of a spring actuated rock shaft releasably held against spring tension, means operated by the rocking of the rock shaft when released for moving the impression

- cylinders out of their printing position, an arm extending from the rock shaft, a rocking segment mounted in the press, a pull bar connecting the segment to the arm, a tension spring connected to the segment so as to exert a pull on the pull bar, a latch pawl holding the segment against spring tension, and tripping finger connected to the latch pawl and extending past the lowered stop finger and into the path of the clutch operating finger as it is freed by the stop finger and returns to the press running position, and means for automatically returning the segment to its latched position after release.
23. In a printing press having an impression cylinder and a printing cylinder, means for positively stopping the impression cylinder at a predetermined position, means for lowering the impression cylinder simultaneously from the printing position, and means for starting and restoring the impression cylinder simultaneously to the printing position.

WALTER HAROLD SMITH.
